BAKING STONE

Pasquale N. Bruno, Elmhurst, and James L. Stewart, Lake Zurich, Ill., assignors to Old Stone Oven Corporation, Elmhurst, Ill.

Filed July 9, 1973, Ser. No. 377,573

Term of patent 14 years

Int. Cl. D7—02

U.S. CL. D7—123

Fig. 1.

Fig. 2.

Fig. 3.

FIG. 1 is a top front perspective view of the baking stone showing our new design;

FIG. 2 is a bottom plan view thereof taken in the direction of the arrows 2—2 shown in FIG. 1; and

FIG. 3 is a cross-sectional view taken on line 3—3 of FIG. 2.

We claim:

The ornamental design for a baking stone, as shown and described.
